UNITED STATES PATENT OFFICE.

JESSE E. KEPPEL, OF ST. LOUIS, MISSOURI.

SIGNAL DEVICE.

1,189,455.

Specification of Letters Patent.

Patented July 4, 1916.

Application filed January 30, 1915. Serial No. 5,167.

To all whom it may concern:

Be it known that I, JESSE E. KEPPEL, a citizen of the United States, residing in the city of St. Louis and State of Missouri, have 5 invented new and useful Improvements in Signal Devices, of which the following is a specification.

This invention relates to signal devices for railroad locomotives, motor cars, and the 10 like.

It has for its object to give a warning to the engineer or motorman in time for him to check the speed of the car or train under his control when approaching a curve, switch, 15 bridge, or other place along the line of the railway where, for reasons of safety, it is necessary to slow down.

In the accompanying drawing illustrating an adaptation of the invention, the figure 20 shows a portion of a railway car equipped with an electrical signal device and a circuit closer which is operated by a device on the roadway.

Referring now to the drawing, the number 25 1 indicates the body of the car, on which is carried a storage or other battery 2. From one pole of the battery leads a wire 3 to an electrical bell 4. From the bell leads another wire 5 to a bracket 6 which is 30 mounted on the under side of the car. Pivoted in this bracket is an arm 7 having a roller 8 journaled in its outer end. The arm 7 is provided, adjacent to the roller 8, with a curved extension or shoe 9 arranged 35 and adapted to engage a contact tongue 10 which is mounted in proximity thereto on the under side of the car and connected by a wire 11 to the pole of the battery 2 opposite to that which is connected to the wire 3. 40 The arm 7 is also provided with a shouldered extension 12 which is connected by a spring 13 to the under side of the car in order that said arm may be yieldably held in normal position out of contact with said tongue 10. 45 Connected in multiple with the wires 3 and 5 is an electric lamp 14, said lamp being provided with the usual circuit-breaker or cut-out button 15.

By the arrangement just described the bell 46 4 is sounded every time the circuit is closed by bringing the arm 7 and tongue 10 into engagement with each other, and the lamp 14 may or may not be simultaneously

lighted, depending whether or not the button 15 is turned to close the lamp circuit. 55

To automatically operate the arm 7 suitable actuating devices are provided at the places along the line of the railway where it is desired to give the signal; that is, within such distance of a curve, switch, bridge, or 60 other place where it is necessary to check the speed of the car or train, in order that the engineer or motorman may have sufficient time to accomplish the same. As shown in the drawing, the actuating device 65 comprises a rail 16 which is arranged in the path of the roller 8 on said arm 7, and at such an elevation that the arm is raised sufficiently to bring the shoe 9 into contact with the spring tongue 10. At the opposite ends 70 of this rail are inclines or curves 17, so that the contact between the shoe 9 and tongue 10 is effected more or less gradually; and the length of the rail is determined by the length of time it is desired to maintain the signal 75 active.

While I have shown in the drawing an electrical signal device, I do not wish to be limited thereby, as the invention comprehends broadly the idea of placing on the 80 car either an audible or an illuminable signal device, or both, and operating the same automatically by the coöperation of a device on the car with another located on the roadway. 85

I claim:

The combination in a railway car, of an electrical signal device on said car, said signal device comprising a supporting bracket, a lever-arm pivotally mounted on said supporting bracket and having a bearing roller near its end, the end portion of said lever-arm being extended and formed to constitute a contact shoe, and said lever-arm having a shouldered extension beyond its pivotal axis 95 arranged and adapted to engage said supporting bracket to limit the normal position of said lever-arm, a spring connected at one end to said lever-arm extension so as to hold the latter yieldably in normal position, and 100 a spring contact member mounted in proximity to said contact shoe portion of said lever-arm so as to be engaged thereby, and means adjacent to the railway in the path of said bearing roller whereby, when the car 105 passes in coöoperative relation thereto said

lever-arm is moved so that its shoe portion is brought into engagement with said spring contact member, said lever-arm and said spring contact being respectively connected to the opposite terminals of the electrical circuit for said signal device.

In testimony whereof, I have hereunto set

my hand in presence of two subscribing witnesses.

JESSE E. KEPPEL.
